COMBINATION TELEVISION RECEIVER AND PICTURE PROJECTOR

Norman H. Young, Jr., Jackson Heights, N. Y., assignor to Federal Telephone & Radio Corporation, New York, N. Y., a corporation of Delaware

Application January 16, 1946, Serial No. 641,582

4 Claims. (Cl. 88—24)

1

This invention relates to a combination television receiver and picture projector and more specifically, to an arrangement for utilizing the optical system of a projection-type television receiver for projecting images from a motion picture machine.

Television receivers which are equipped with apparatus for projecting images from the face of a cathode ray tube to the viewing screen of the receiver may be very readily adapted for projecting slide or motion picture images, thus employing to good advantage the excellent optical qualities of such projection receivers. One well-known rear projection system, for example, uses a translucent plastic screen which has both front and rear faces shaped to secure uniform distribution of light over the entire screen area, and the front face is further provided with ridges to insure a wide angle of light distribution in the horizontal plane. It would be especially desirable, therefore, to utilize the screen of such a projection system for the display of projected pictures as well as television images, and the present invention makes this possible.

Hence, one object of this invention is to provide an arrangement for employing the high efficiency screen of a projection television receiver for displaying the images projected from a motion picture machine.

A second object is to provide an arrangement for introducing motion picture images into the optical system of a projection type television receiver.

The excellent optical efficiency of translucent television screens may result in very bright pictures when motion picture projectors are used having bulbs which produce light intensities such as would be required for ordinary use of the motion picture machines. Smaller projection bulbs might easily be used to produce images on the screen with a desired brilliancy, hence a saving in power and a possible simplification of the cooling system of the projector may be realized also.

A further object is to provide an optical system, for use with a motion picture projector, which produces a picture having improved brilliancy characteristics.

A still further object of this invention is to provide an optical system, for use with a motion picture projector, whose high optical efficiency permits the use of relatively small light sources and simplified projector cooling arrangements.

The foregoing objects and features of the present invention may be more clearly under-

stood and others may become apparent from a discussion of one particular embodiment thereof, reference being had to the drawing in which:

Figure 1 is a partial pictorial section of the mechanical and optical structure of one possible combination of a television receiver and a motion picture projection system.

Figure 2 is an alternative combination of a television receiver and a motion picture projection arrangement, the optical system being shown only in part.

In Figure 1, a television receiver cabinet 1 is shown enclosing an optical arrangement which projects a televised image from the face 2 of a cathode ray tube 3 to a translucent screen 4. Intermediate the tube and screen are a spherical mirror 5 reflecting the images on the face 2 of the tube, a plastic correcting lens 6 and a plane mirror 7. This system suffices for projection of the receiver images, however, in accordance with my invention, a motion picture projector 8 is also provided, and an auxiliary mirror 9 is mounted to deflect light from the projector up to the plane mirror 7 and the screen 4. The motion picture projector 8 is shown mounted on the hinged door 10 on the front of the cabinet and a lever system 11 is connected thereto and to the mirror 7, so that opening the door swings the mirror to the position sketched and closing it causes the mirror to line up with the longitudinal axis of the cathode ray tube 3.

The mirror 7, if made sufficiently small, might not detract from the performance of the television optical system even when in a position to reflect light from the projector 8, because the cathode ray tube already intercepts a portion of light in the center of the optical system, without interfering with the projections, in which case the lever system 11 may be omitted. The projector may or may not be rigidly attached to the door 10 of the cabinet depending primarily upon space considerations. Large amounts of waste space are usually found in such optical systems, however, and storage space for the projector or film might be located at positions such as indicated at 12, in the drawing. The entire arrangement is especially advantageous and applicable to home television receivers.

The arrangement of Figure 2 illustrates an alternative method of introducing the image from a picture projector 8 into the optical system of the television receiver enclosed by the cabinet 1. This method involves projecting the image from the projector 8 to the face 2 of the television tube 3 through the opening 13 in the spher-

ical mirror 5, already provided for other reasons. Projection of the image to the translucent screen 4, not shown in this figure, is accomplished just as if the projected picture image were a received television image. The picture projector 8 is supported in an appropriate position by a bracket 14, and changing of film and other adjustment might be facilitated by a hinged door in the cabinet and possibly a means for moving the projector to a convenient location when access thereto is required.

Several changes may be instituted by those skilled in the art without departing in principle from this invention; for example other means for mounting the motion picture projector or other means for rotating or moving the auxiliary mirror might be provided, or, the motion picture images might be projected into the optical system from positions other than those illustrated and described heretofore. Although only two embodiments of the invention have been shown and described, the scope of the invention should not be considered limited thereby.

I claim:

1. A combination television receiver and motion picture projector, comprising a rear projection television receiver having a cathode ray tube positioned vertically with its fluorescent screen bottommost, a spherical mirror reflecting upward the images from said fluorescent screen, a plane translucent screen mounted vertically, a plane mirror reflecting the image from said spherical mirror to said screen, and a correcting lens positioned between said spherical mirror and said plane mirror; a motion picture projector; means for mounting said projector; and an auxiliary reflecting system located above said cathode ray tube between said correcting lens and said plane mirror and substantially in alignment with the longitudinal axis of said cathode ray tube, said auxiliary reflecting system being directed to reflect light from said projector to said plane mirror.

2. A combination television receiver and motion picture projector according to claim 1 where-
in said auxiliary reflecting system comprises an auxiliary mirror movable from a position most favorable for reflection of light from said picture projector to said plane mirror to a position in which minimum interference occurs to projection of televised images, and means for moving said auxiliary mirror to desired positions.

3. A combination television receiver and motion picture projector, comprising a rear projection television receiver and housing structure

5 having a cathode ray tube positioned vertically with its fluorescent screen bottommost, a spherical mirror reflecting upward the images from said fluorescent screen, a plane translucent screen mounted vertically, a plane mirror reflecting the images from said spherical mirror to said screen, and a correcting lens positioned between said spherical mirror and said plane mirror; a motion picture projector; means for mounting said projector; an auxiliary mirror located above said cathode ray tube between said correcting lens and said plane mirror and rotatable from a position in which it reflects maximum light from said projector to said plane mirror to a position in which it least interferes with the projection of televised images; and means for rotating said auxiliary mirror to the desired positions.

4. A combination television receiver and motion picture projector according to claim 3 where-
in said means for mounting said projector comprises a hinged section of said housing which may be opened to serve as a support for said projector or which may be closed to aid in enclosing said television receiver, and wherein said means for rotating said auxiliary mirror comprises a linkage, between said hinged section and said auxiliary mirror, which rotates said auxiliary mirror into said position in which it reflects maximum light from said projector to said plane mirror when said hinged section is opened and which rotates said auxiliary mirror into said position in which it least interferes with the projection of televised images when said hinged section is closed.
